DESIGN FOR A HOLDER FOR UPPER BOWL OF VACUUM COFFEE BREWING DEVICES

John W. Haffner, Culver City, Calif.

Application September 13, 1947, Serial No. 141,385

Term of patent 3½ years

(Cl. D44—26)

To all whom it may concern:

Be it known that I, John W. Haffner, a citizen of the United States of America and a resident of the city of Culver City, in the county of Los Angeles and State of California, have invented a new, original, and ornamental Design for Holder for Upper Bowl of Vacuum Coffee Brewing Devices, of which the following is a specification, reference being had to the accompanying drawing, forming part thereof.

In the drawings:

Figure 1 is a perspective view of a holder for upper bowl of vacuum coffee brewing devices, showing my new design therefor, and

Figure 2 is a rear elevational view thereof shown on a commensurate scale.

I claim:

The ornamental design for a holder for upper bowl of vacuum coffee brewing devices, substantially as shown.

JOHN W. HAFFNER.
